UNITED STATES PATENT OFFICE.

FERDINAND M. BARTELME, OF CHICAGO, ILLINOIS.

MECHANICAL GEAR-SHIFTING DEVICE.

Application filed December 8, 1921. Serial No. 520,913.

My invention relates to mechanical devices whereby speed changes in a variable speed transmission mechanism may be effected through the agency of a pre-selecting mechanism and an actuator that is readily and conveniently operated.

More particularly my invention relates to mechanical devices for effecting speed changes in a variable speed transmission mechanism 10 of an automobile which may or may not be adapted, as desired, to also actuate the braking means of the automobile.

One object of my invention is to provide a device of the character designated above 15 which will be compact in construction and easily applied to variable speed transmission mechanisms of the standard and usual type. By reason of the compactness of my device, the same may be applied to automobiles as at 20 present constructed without having any parts extending above the floor boards of the automobile that may cause inconvenience to the operator. By means of my present invention, a mechanism of improved construction is provided which obviates the necessity 25 for manually operative gear shifting levers.

A further object of my invention is to provide a gear shifting device which may be operated by the positive actuation of a foot 30 pedal. In this manner, the gear shifting operation effected within the variable speed transmission mechanism may be expeditiously performed without the clashing of gears since it is possible to "feel in" the gears into the 35 various meshing relations.

Another object of my invention is to provide a gear shifting device which permits of the pre-selecting operation to be performed at 40 any time irrespective of the position of the actuating foot pedal in its path of travel.

Moreover, the gear shifting operations by my device may be performed without the necessity of following a certain sequence of operations. In this manner, a pre-selected 45 speed change may be arranged for subsequent performance when one speed change in the transmission mechanism is in operation.

Another object of my invention is to provide a device which may be operated through 50 the agency of a foot pedal which may be the clutch pedal that also actuates the clutch mechanism. In this instance, the pre-selection may be effected when the clutch is en-

gaged or disengaged or when the clutch pedal 55 is at either end of its path of travel or in any intermediate position.

Another object of my invention is to provide a gear shifting device in connection with a pre-selecting mechanism which, after a 60 pre-selected speed change has been effected and while the pre-selecting mechanism has been retained in the position corresponding to this pre-selected speed change, subsequent actuations of the foot pedal or clutch pedal 65 will not operate to disconnect the meshing relation previously established in transmission mechanism to effect this speed change.

Another object of my invention is to provide a gear shifting device comprising a selective neutralizer whereby an established meshing relation within the transmission mechanism is retained on subsequent actuations of the foot or clutch pedal until a new setting of pre-selecting mechanism has been 75 made. In this manner there is no possibility of the speed change gears comprised in the transmission mechanism from becoming disengaged or partly disengaged from their meshing connection until it is desired 80 by the operator that a new speed change be effected.

Another object of my invention is to provide a device of the character indicated above 85 which comprises means operative through a pre-selecting mechanism which will apply braking action to the automobile through the agency of the clutch pedal. In connection with this braking means, I also provide auxiliary means that are readily accessible to the 90 operator for retaining the braking action in operation whereby the first set of braking means may be released to permit of my device being operated then as a gear shifting device.

A further object of my invention is to provide a device which will be compact in construction, readily applied to the standard forms of speed transmission mechanisms and economical to manufacture.

Other objects of my invention will be hereinafter pointed out, but for a better understanding of the device of my present invention, reference may now be had to the following description and accompanying drawings, in which—

Figure 1 is a diagrammatic view of a portion of an automobile chassis embodying my present invention;

Fig. 2 is a plan view of my device with the casing cover removed and the elements therein shown as occupying "neutral" position;

Fig. 3 is a view, partially in section, taken on the line 3—3 of Fig. 2 and showing a portion of a variable speed transmission mechanism with which my device is associated;

Fig. 4 is an end view of the device taken on the line 4—4 of Fig. 3;

Fig. 5 is a sectional view taken on the line 5—5 of Fig. 3;

Fig. 6 is a side sectional view taken on the line 6—6 of Fig. 5;

Fig. 7 is a horizontal section on the line 7—7 of Fig. 4 but showing, however, some of the elements arranged to effect a speed change in the transmission mechanism to "first";

Fig. 8 is a view similar to that of Fig. 7 but showing some of the elements in such positions as to effect a change speed in the transmission mechanism to "second";

Fig. 9 is a perspective view of that portion of my mechanism which I have designated as the actuator;

Fig. 10 is a plan view in development of a portion of my device with the mechanism of Fig. 9 removed therefrom and the two upper shifting bars out of their operating positions but placed adjacent to their corresponding locations in the assembled device;

Fig. 11 is a perspective view showing one of the shifting rods embodied in my device;

Fig. 12 is a perspective view of a gear holding fork that is secured to the shifting rod of Fig. 11 and, in turn, engages one of the speed change gears of the variable transmission mechanism;

Fig. 13 is a perspective view of a member comprised in the actuator mechanism of Fig. 9;

Fig. 14 is a perspective view of another member of the actuator mechanism of Fig. 9;

Fig. 15 is a view in elevation of a portion of the structure of Fig. 1 showing how the braking means of the automobile may be retained in operative position after having been first actuated through the agency of my present device; and

Fig. 16 is an enlarged view of a portion of the structure of Fig. 1 showing the manner in which the automobile clutch mechanism may be operated by the clutch pedal during the time that my device is holding one of the speed-change gears in engagement to effect a certain pre-determined speed change in the transmission mechanism.

Referring to Fig. 1, the automobile chassis comprises a usual steering wheel 1 which is mounted upon a steering-wheel post 2 that is hollow and through which a rotatable rod 3 extends. The upper end of the rod 3 is secured to a rotatable index finger 4 which operatively engages with an indicating sector 5. The latter serves as an indicating medium

for the various operations to be performed, the recesses 5' upon the sector 5 being properly designated in order that the index finger 4 may be positioned in any one of said recesses at will in accordance with the selected operation to be subsequently performed. Through the agency of the index finger 4, the rod 3 is rotated which, in turn, actuates a gear train enclosed in a housing 6 at the base of the steering-wheel column 2. The gear train 6 imparts a rotary motion to a connecting rod 7 through a universal joint 8 and this rod 7, is, in turn, connected to a rotatable member 9 of a second universal joint 10. The member 9 is journaled in a sleeve 11 forming part of a housing 12 that encloses the mechanism or gear shifting device embodying my present invention.

The housing 12 is mounted upon the casing which contains the variable speed transmission mechanism of the automobile. The rear-axle drive mechanism 13' of the automobile is furnished with power through a drive shaft 13, the speed of which may be varied, as well as the direction of rotation, through the variable speed transmission mechanism with which the device of my invention is associated. It is to be understood, of course, that the variable speed transmission mechanism may be any of the usual types employed in automobile construction and especially those of the sliding-gear type. In the present instance, the variable speed transmission mechanism of the automobile provides for the usual forward speeds, namely, first, second and third speeds and one reverse speed.

The index finger 4, in addition to performing other functions, serves to pre-select any one of the said several speed changes that may be made in the variable speed transmission mechanism. The pre-selected operation or speed change indicated by the position of the index finger 4 on the sector 5 is then effected through the operation of a clutch pedal 14 which is connected to a lever 15 journaled in a stationary stub sleeve 16. The clutch pedal 14 operates in the usual manner. The clutch mechanism of the automobile which, in this instance is shown as being a cone clutch, comprises a clutch member 17 and a fly wheel member 18 which is secured to the driving shaft 19 of the automobile engine. The clutch pedal 14 actuates a shaft 20 which, in turn, operates to effect engagement and disengagement of the clutch mechanism. A compression spring 21 normally holds the two members 17 and 18 of the clutch mechanism in engagement and the speed transmission mechanism is connected to the automobile engine through this clutch mechanism.

The clutch-pedal lever 15 is provided with an extension 22 to which a rod 23 is secured to one of its ends. The other end of the rod 23 is pivotally secured at 24, through a lost

motion joint, to a lever 25 that is pivoted on a shaft 26 mounted upon a rearwardly extending bracket 27 cast integrally with the housing 12. The lever 25 is provided at its outer end with a forked portion 28 which embraces a collar 29 of a rotatable and slideable member 30.

From the foregoing, it will be observed that the clutch pedal 14, in addition to effecting engagement and disengagement of the cooperating clutch members 17 and 18, also operates to move the rod 30 which comprises one of the operating elements of my present mechanism.

15 A brake rod 31, the operation of which will be hereinafter described in detail, extends from the housing 12 of my gear shifting mechanism and is adapted to reciprocate in the sleeve 32. The rod 31 is connected through 20 a lost-motion joint 33 to a rock shaft 34 which, in turn, operates to rotate a shaft 35 that is journaled in sleeves 36 secured to the automobile chassis. The shaft 35 actuates two pull rods 37 which serve to tighten band 25 brakes 38 which engage the rear wheels of the automobile. The band brakes 38 and the mechanism immediately serving to contract and expand them is old in the art and may be of any of the usual types of construction 30 which is in common use in automobiles. It is to be noted that the band brakes 38 may be tightened by causing the brake rod 31 to travel in the direction of an arrow 39.

35 A second brake rod 40 is likewise connected to the rock shaft 35 through a lost motion joint 41. The rod 40 is manually operated, as will be described later, to hold the rock shaft 35 in operative position after having been so placed through the agency of the brake 40 rod 31. After the brake rod 40 has been properly manipulated to hold the rock shaft 35 in operative position to tighten the band brakes 38, the brake rod 31 may then be released from operative engagement with the rock shaft 45 35 which is permitted by reason of the lost motion provided in the joint 33.

As hereinbefore described, the housing 12 is mounted upon the casing which encloses the variable speed transmission mechanism of the automobile as shown in Figs. 2 and 3 to which reference may now be had. The speed transmission mechanism of the automobile is housed in a casing 42. The enclosed transmission mechanism, a portion only of which is shown in the present exemplification of my invention, comprises slideable gears 43 and 44 that are severally provided with collars 45 and 46 respectively which are engaged by forked members 47 and 48 of a 50 form such as is illustrated in Fig. 12. The forked members 47 and 48 are secured to downwardly extending arms 49 and 50 respectively by means of screw bolts 51. The downwardly extending arms 49 and 50 are 55 severally connected to elements comprised in

my gear shifting mechanism. The slideable gears 43 and 44 are shown in Fig. 3 as occupying "neutral" position but they may be shifted into different meshing relations with the other gears comprised in the transmission 70 mechanism to effect the desired speed changes, such meshing relations giving neutral position and first, second, third and reverse speeds. The top of the casing 42 is closed by a base plate 52 forming a part of 75 a housing 12. The base plate 52 is provided with openings at the proper locations to permit of the downwardly extending arms 49 and 50 to project from the housing 12 into the transmission casing 42 and also to permit 80 these same arms to move unimpeded so as to position the slideable gears 43 and 44 as desired, and to permit oil to splash therein.

As mentioned above, the member 9 of Fig. 2 is rotated by means of the pre-selecting 85 mechanism comprising the index finger 4 and the positioning sector 5. The rotary motion imparted to the member 9 is transmitted to the rotatable and slideable rod 30 through a gear train comprising a driving gear 53, 90 an idler 54 and a driven gear 55. The rod 30 is splined to the gear 55 by means of a key 56 that extends longitudinally of the rod 30. It will be seen that the rod 30 may, in this manner, be rotatably positioned to correspond with the setting of the index finger 4 upon the indicating sector 5. Irrespective of the rotatable position of the rod 30, the same may be moved longitudinally in all positions. By means of the lever 25, which derives its 100 movement from the actuation of the clutch pedal 14, the rod 30 is moved forwardly in opposition to the force exerted by the compression spring 21 of the clutch mechanism. The rod 30 is restored to its normal position 105 when the clutch pedal 14 is returned to its normal position in the usual manner. The forked end 28 of the lever 25, which engages the collar 29 secured to the outer extremity of the rod 30, actuates the rod 30 in accordance with the movements of the clutch pedal 14. From the foregoing, it will be seen that the rod 30 is subjected both to rotatable movement, as well as a sliding movement, and through the medium of this rod 30, the device 110 of my present invention is actuated.

Attention is now directed to Figs. 9 and 10, the former being a perspective view of the actuator mechanism comprised in my device and the latter being a plan view in development showing the arrangement of the shifting bars that are adapted to be selectively engaged by the actuator mechanism to perform the operations indicated by the pre-selecting mechanism constituting the members 125 4 and 5. The actuator mechanism of Fig. 9 comprises an integral stationary block 57 shown in dotted lines. This block 57 is substantially symmetrical about a central longitudinal plane and is provided on its front face 130

with a stationary sleeve member 58, both the block member 57 and the sleeve member 58 being bored uniformly to receive a sliding tubular member 59 which is provided at its front end with a flange 60 that is adapted, when in normal position, to abut against the exposed face of the sleeve 58. The tubular member 59 is provided at its rear end with a sleeve 61 which is secured thereto by means of screws 62. The side of the block 57 which is exposed to view in Fig. 9, is provided with an integrally formed lateral extension or ledge 63 which projects substantially midway between the upper and lower faces of the block 57. The lateral extension 63, intermediate its ends is recessed to receive a rotatably mounted pinion 64. A face plate 65 is also received in the recess containing the pinion 64 and provides a flush and continuous side surface for the ledge 63. It will be observed that the pinion 64 is exposed on both the upper and lower faces of the ledge 63 as shown in Fig. 5. The side of the block 57 opposite to the side exposed to view in Fig. 9, is likewise provided with a correspondingly positioned ledge 67 which likewise receives a rotatable pinion 66 (Fig. 5) that is housed in a recess formed in the ledge 67. The pinion 66 also is exposed at the upper and lower faces of the ledge 67 in a manner similar to the pinion 64. Both pinions 64 and 66 are shown as having the same diameter and each comprises the same number of gear teeth. The upper face of the block 57 comprises a smooth surface which is flush with the upper edge of the housing 12. The lowermost portion of the block member 57 is provided with a plurality of downwardly extending projections 68, 69, 70 and 71, the purposes of which will be explained in connection with the mechanism illustrated in Fig. 10.

The tubular member 59 is provided at its outer end with the flange 60 which serves as a selective neutralizer and the purposes of which will be subsequently explained in detail. The position occupied by the tubular member 59, as shown in Fig. 9, is approximately the position corresponding to "neutral" position of the gear shifting mechanism. It will be observed that the uppermost portion of the tubular member 59 is provided with two aligned and spaced longitudinal slots 72 and 73, the former being a comparatively short slot and the latter being a comparatively long slot. The uppermost portion of the neutralizer 60 is also slotted as at 74, the slot 74 extending across the entire face and thickness thereof. The tubular member 59 is adapted to slidably engage in the bore provided by the sleeve 58 and the block 57. Fig. 14 shows the tubular member 59 in a position 180° from its position in Fig. 9. The under side of the tubular member 59 is shown as being provided with a lon-

gitudinally extending slot 75 and the under side of the neutralizer 60 is shown as being provided with a recess 76, the top inner surface 77 of which is chamfered downwardly and inwardly. Similarly, the rear end of the slot 73 (Fig. 9) is chamfered to provide an inwardly sloping surface 78.

A cylindrical member 79 of Fig. 13 is slidably received in the tubular member 59 of Figs. 9 and 14. The cylindrical member 79 is secured at its front end to the rod 30. A rotatable hardened steel annulus 80 abuts against the outer face of the member 79 and is held against longitudinal movement by means of the key 56. A latch member 81 is positioned transversely in the forward end of the cylindrical member 79 and is provided with a latching portion 82 and an opposed latching portion 83. The latch member 81 is permitted to slide transversely of the cylindrical member 79 but is attached thereto by means of a pin 84. The rear end of the tubular member 79 is provided with two co-acting latch members 85 and 86 which extend transversely of the cylindrical member 79 in a manner similar to the latch member 81. Both latch members 85 and 86 are adapted to be moved transversely of the member 79 and oppositely to each other since they are geared to each other, as will be hereinafter described. The latch members 85 and 86 are provided with oppositely disposed chamfered ends as shown.

In assembled position, (Fig. 9) the cylindrical member 79 with its appurtenances, is received within the tubular member 59 with which it slidably engages. The latch member 81 is received within the recesses 74 and 76 of the neutralizer 60 and the latches 85 and 86 may be received in the slots 72 and 73, and the opposed slot 75 but, as shown in Fig. 9, the latch 86 is received in the slot 72 and the latch 85 in the slot 73.

Attention may now be directed to Fig. 8 in order to secure a better understanding of the operation of the latch members 81, 85 and 86. The latch member 81 is provided with a longitudinal slot 87 through which the pin 84 extends. Its rear face is provided with a V-shaped recess 88 in which a spring-pressed hardened steel ball 89 is normally received. The ball 89 is positioned in a recessed plug member 90 that slidably engages in a central longitudinal opening 91 formed in the cylindrical member 79. A compression spring 92 contained within the central opening 91 presses the ball 89 against the latch member 81. The normal position of the latch member 81 is shown in Figs. 8 and 9 and, in this position, the latch portion 82 is completely exposed to effect operative engagement with the shifting rods of my device. The rear end of the cylindrical member 79 is likewise provided with a spring pressed plug 90' which, in turn, presses a ball 89' into a

recess 88' formed in the front face of the latch member 85. The latch member 85 is provided at one end with a latch portion 93 comprising one inclined surface and at the 5 opposite end with a latch portion 94 comprising two opposed inclined surfaces which form a V-shaped head similar to the V-shaped head of the latch portion 83 of the latch member 81. The latch member 86 is provided 10 with latch portions 95 and 96, each constituting a single inclined operating surface. The opposed and adjacent surfaces of the latch members 85 and 86 are provided with gear teeth 97 which engages on opposite sides 15 with a pinion 98 that is rotatably mounted upon a pin 99. It will thus be observed that the latch members 85 and 86 are geared to each other and that an upward movement of one latch member causes a downward movement of the other latch member and vice 20 versa.

The latch members 85 and 86, as well as the latch member 81, are operated as the cylindrical member 79 slidingly engages within 25 the tubular member 59. For instance, the cylindrical member 79 is shown in Fig. 8 as occupying one of its rotatable positions in which it is advanced forwardly and withdrawn from the tubular member 59 as far as 30 possible. In this circumstance, the latch portion 82 of the latch 81 is projected outwardly to its extreme position from the cylindrical member 79 and, as a consequence, the latch portion 83 is drawn completely within the 35 cylindrical member 79. Now, as the cylindrical member 79 is slid inwardly of the tubular member 59, the latch portion 82 will eventually engage a projecting tooth 100 which, for the time being, is stationary. The latch portion 82 is then about to be received in the 40 slot 74 formed in the neutralizer 60. When engagement between the latch portion 82 and the tooth 100 is effected, further movement forces the latch portion 82 downwardly into the cylindrical member 79 which, in turn, causes the opposed latch portion 83 to project outwardly from the cylindrical member 79 and into the recess 76 likewise formed in the neutralizer 60. Further inward movement 45 of the cylindrical member 79 causes the inclined surface of the latch portion 83 that is adjacent to the chamfered surface 77 to come into engagement therewith. The neutralizer 60 being stationary after abutting the 50 sleeve 58 and, therefore, the chamfered surface 77 of the recess 76, further inward movement of the cylindrical member 79 effects sliding engagement between the latch portion 83 and the chamfered surface 77 and this, in 55 turn, forces the latch portion 83 again inwardly of the cylindrical member 79 and the latch portion 82 outwardly therefrom. At this time, the latch portion 82 projects outwardly of the member 79 on the rear side of 60 the tooth 100 and has its plane face in abut- 65

ment to the plane face formed on the rear of the tooth 100. When the latch portion 82 occupies its outermost position relative to the cylindrical member 79, the spring pressed ball 89 serves to retain the latch member 81 in this, its normal position.

When the cylindrical member 79 is in such a position wherein the latch portion 82 of the latch 81 extends to the rear of the tooth 100 it is necessary, in order to permit the cylindrical 75 member 79 to be advanced forwardly and withdrawn from the tubular member 59, that the cylindrical member 79 be rotated in order to avoid the obstruction offered by the tooth 100 to the latch portion 82. The means provided for rotating the cylindrical member 79 in order to permit the latch portion 82 to pass the tooth 100 constitutes the rotatable rod 30. For the moment, however, it is to be noted that when the latch portion 82 is projecting outwardly from the cylindrical member 79 and to the rear of the tooth 100, the cylindrical member 79 is permitted a certain range of longitudinal movement within the tubular member 59, which range is comprehended within the 80 length of the recess 74 formed in the neutralizer 60. As will be observed later, this range of relative movement between the member 79 and within the tubular member 59, when the latch portion 82 is at the rear of the tooth 100, 85 may be sufficient travel to permit of engagement and disengagement of the members 17 and 18 comprising the clutch mechanism of the automobile, but the loose joint 24 (Fig. 16) allows further travel to the clutch pedal 100 to ensure this action.

Consider now the conjoint action of the latch members 85 and 86 when the cylindrical member 79 is drawn inwardly of the tubular member 59. The inclined surface of the latch portion 93 of the latch 85 will eventually engage the chamfered surface 78 formed at one end of the slot 73 as shown in Figs. 8 and 9. This engagement will force the latch member 85 downwardly and, as a consequence, will 110 cause the latch member 86 to move upwardly by reason of the coaction between the two latch members 85 and 86 which is effected by the interposed pinion 98. The latch portion 95 of the latch 86 will then be extended outwardly from the cylindrical member 79 and received in the slot 79 in the manner shown in Fig. 9. In this position, the latch portion 96 of the latch member 86 is drawn completely 115 into the cylindrical member 79 and the latch portion 94 of the latch member 85 is projected as far as possible outwardly and downwardly from the cylindrical member 79. In this position, the latch portion 94 projects through the slot 75 and in abutting relation to a chamfered surface 101 that is formed on the rear periphery of the bore in the block 57 wherein the tubular member 59 and the cylindrical member 79 are received. As long 120 as the latch portion 95 projects upwardly in 125

the slot 72 it will abuttingly engage with the forward end wall of the slot 72 and restrict the relative sliding movement of the cylindrical member 79 within the tubular member 59. The range of this limited movement is confined to the length of the slot 72 and it is equal to the range of movement allowed to the projecting latch portion 82 of the latch 81 when it extends upwardly and to the rear 10 of the tooth 100. In order to withdraw the latch portion 95 from the slot 72, thereby permitting the cylindrical member 79 to slidingly engage unimpededly within the tubular member 59, it is first necessary, as explained above, to rotate the cylindrical member 79 so as to withdraw the latch portion 82 of the latch member 81 from obstructing engagement with the tooth 100. When this operation is effected, the latch portion 94 of the 20 latch member 85 is then permitted to slidingly engage with the chamfered surface 101. The engagement effected between the surface 101 and the adjacent inclined surface of the latch portion 94 forces the latch member 85 inwardly of the cylindrical member 79 and simultaneously therewith the latch portion 95 of the latch member 86 is likewise drawn inwardly of the cylindrical member 79, thereby releasing engagement between the cylindrical member 79 and the tubular member 59 which heretofore had been effected by reason of the latch portion 95 being received in the slot 72. When the latch portion 95 is withdrawn from the slot 72, the cylindrical member 79 is permitted to slide forwardly within the tubular member 59. This range of sliding engagement between these two members 59 and 79 is limited only by the length of the slot 73 wherein the latch portion 93 of the latch member 85 is received.

The sleeve 61 serves to retain the latch member 86 in the cylindrical member 79 and precludes it from being projected from the slot 72 should the latch member 85 violently engage with the chamfered surface 78. The foregoing description in connection with Figs. 8, 9, 13 and 14 illustrates the conjoint operation between the tubular member 59 and the cylindrical member 79 which comprises the various latch members.

The mechanism of Fig. 9, which I have designated as an actuator, may be assembled as a unit before being placed into operative engagement with the mechanism illustrated in Figs. 4, 5, 6 and 10 to which attention is now directed. A plurality of sliding bars 102, 103, 104, 105, 106 and 107 (Fig. 10) which constitute shifting rods, are adapted to be selectively operated by means of the actuator mechanism of Fig. 9. The bar 103 is positioned upon a ledge 108 integrally formed in the housing 12. The bar 103 slidingly engages upon this ledge and has secured thereto the brake rod 81 and, also, is provided at its front portion with an upstanding tooth 109.

Intermediate its end portions, a rack 110 is formed which is adapted to engage with the pinion 64 of the actuator. Superimposed upon and spaced from the sliding bar 103 is the sliding bar 102 which is provided at its front portion with an upstanding tooth 111 and at its intermediate portion with a rack 112. The rack 112 faces oppositely to the rack 110 and is adapted to likewise engage with the pinion 64 which, when the actuator 75 of Fig. 9 is in operative position in the gear shifting mechanism, is disposed intermediate the racks 110 and 112 thereby permitting operative engagement therewith as shown in Fig. 5. The sliding bar 104 engages the surface of the bottom 52 of the enclosing casing 12 as does the sliding bar 105 which is spaced therefrom and placed oppositely thereto. The front end of the bar 104 is provided with an upstanding tooth 113 and in alignment therewith the bar 105 is likewise provided with an upstanding tooth 114. The bars 104 and 105 are also severally provided with upstanding teeth 115 and 116, respectively, which are normally placed in alignment with the upstanding tooth 100 which has been described in detail in connection with the mechanism of Fig. 8. The opposed and adjacent sides of the sliding bars 104 and 105 are provided with racks 117 and 118, respectively, which are adapted to engage with a rotatable pinion 119 that is journaled to a jack shaft 120 mounted on the bottom 52 of the housing 12. It will be noted that the sliding bar 104 is provided with a series of spaced indentations 121 on its outer side which are adapted to receive a spring pressed pin of a poppet 122 that is mounted on the casing 12 as shown in Fig. 5. The purpose of the poppet 122 is to restrain the movement of the sliding bar 104 as it assumes the various positions of which it is capable. By reason of the coacting engagement between the sliding bars 104 and 105, through the agency of the pinion 119, the bar 104 as it advances forwardly causes the bar 105 to advance rearwardly and vice versa. The sliding bar 106 is disposed upon a ledge 122 (Fig. 4) in a position opposite to the sliding bar 103. The bar 106 is provided at its front portion with an upstanding tooth 123 and the upstanding tooth 100 hereinbefore described. A rack 124 is formed on the upper face of the sliding bar 106. The sliding bar 107 is superimposed upon the sliding bar 106 and placed oppositely thereto in order to permit of the interpositioning of the pinion 66 of Fig. 5. The bar 107 is also provided with a rack 125 cut on its lower face, and when in assembled position, engages the pinion 66 in conjunction with the rack 124 formed on the sliding bar 106. The sliding bar 107 is provided at its front portion with an upstanding tooth 126 and spaced therefrom with a second upstanding tooth 127. A series of spaced re- 125

cesses 128 are cut in the outer side of the sliding bar 107 and are adapted to receive a spring pressed pin 129 (Fig. 4) which is comprised in a poppet 130. The poppet 130 serves to restrain movement of the sliding bar 106 in any of the several positions that it may assume. An interlock 129^a provided with inclined locking ends 130^a and 132 extends transversely of the sliding bars 104 and 105 and is adapted to be received in a recess 133 formed in the sliding bar 106 or a recess 134 formed in the sliding bar 104. It is to be noted that the interlock 129 serves to retain the sliding bar 106 in position when the sliding bar 104 is advanced forwardly or rearwardly and similarly the bar 105 in position when the sliding bar 106 is advanced forwardly or rearwardly.

The sliding bars are shown in Fig. 10 as occupying their neutral positions, assuming, of course, that the sliding bars 102 and 107 are placed in their operative positions within the casing 12 as shown in Figs. 4 and 5. In this circumstance, the plane rear faces of the foremost upstanding teeth 111, 109, 113, 114, 123 and 126 are co-incident and similarly the plane rear faces of the upstanding rear teeth 115, 116, 100 and 127 may be co-incident. The group of upstanding foremost teeth 111, 109, 113, 114, 123 and 126 are so designed that in the aggregate they form the segment of a circle when the associated sliding bars are all in neutral position, as shown in Fig. 4 and similarly the upstanding rear teeth 115, 116, 100, 127 may constitute the segment of a circle.

The particular device shown herein is adapted to be used in connection with a variable speed transmission mechanism comprising two slidable gears having a uniform length of throw for all speed changes and the following operations of the sliding bars of Fig. 10 effect the various speed changes in the transmission mechanism and the application of the hand brakes of the automobile. When the sliding bar 102 is advanced forwardly, the sliding bar 103 is advanced rearwardly in the direction of the arrow 31' and, consequently, exerts a pull upon the brake rod 31. Therefore, the sliding bar 102 may be designated as the brake bar. When the sliding bar 104 is advanced forwardly, the proper slidable speed change gear comprised in the variable speed transmission mechanism of the automobile is brought into meshing relation to effect "reverse" speed. The downwardly projecting lug 50 of Figs. 3, 4 and 5 is integrally formed with the sliding bar 104 and the forked member 48 is, in turn, secured to the lug 50 whereby the shiftable speed-change gear 44 of Fig. 3 may be moved into meshing relation in the transmission mechanism. As the sliding bar 104 is advanced forwardly, the sliding bar 105 is advanced rearwardly. To effect a speed change in the transmission mechanism to "first," the sliding bar 105 is advanced forwardly and this, in turn, causes the sliding bar 104 to advance rearwardly which, in turn, moves the slidable gear 44 of Fig. 3 (from its meshing connection of "reverse" through neutral position and into a new meshing connection) to effect a speed change into "first." When the sliding bar 106 is advanced forwardly, the downwardly projecting lug 49 of Fig. 3, which is integrally formed with the rod 106, is likewise advanced forwardly and this, in turn, actuates the slidable speed change gear 43 to effect a meshing engagement in the transmission mechanism to establish "second" speed. When the sliding bar 107 is advanced forwardly, the speed transmission mechanism is brought into "third" speed, since the sliding bar 106 is then advanced rearwardly and, in conjunction therewith, the slidable gear 43 is unmeshed from "second" speed relation, carried through neutral position and into a new meshing relation to establish "third" speed in the transmission mechanism. The arrow 135 affixed to Fig. 10 indicates "forward" direction for moving the several sliding bars. If the speed change gears 43 and 44 have different lengths of throw to effect the various speed changes, the upstanding teeth of the rear group must be located correspondingly and, in this instance, the teeth of the rear group will not be coincident.

In assembling my device, the mechanism of Fig. 9 is so positioned with reference to the assembled elements illustrated in Fig. 10 that the projections 68 and 69 formed on the lower face of the block 57 are disposed on opposite sides of the pinion 119 and the projections 70 and 71 form a housing for the interlock 129. The block member 57 is then fixed in position, in any suitable manner, in order to preclude any movement relative to the casing 12. Then the sliding rods 102 and 107 are placed in their respective positions as shown in Figs. 4 and 5.

To more clearly explain the coaction between the sliding bars 106 and 107, and likewise the corresponding bars 102 and 103, reference may be had to Fig. 6 wherein the sliding bars 106 and 107 are shown in assembled position and when occupying "neutral." It will be noted that the pinion 66 engages the racks 124 and 125 formed respectively on the bars 106 and 107 since the pinion 66, as well as the corresponding and opposite pinion 64 is precluded against any longitudinal movement by reason of their being secured to the fixed block 57. The two coacting shifting bars 106 and 107 are permitted to slidably engage with the side face of the block 57. By again referring to Figs. 9 and 10, it will be observed that when my device is assembled, the shifting bar 104 is slidably received in the lowermost longitudinal recess formed in the block 57, the shifting bar 103

is slidingly received in the bottom recess formed by the longitudinally extending ledge 63 and the shifting bar 102 is slidingly received in the upper recess formed by the ledge 63. Similarly the sliding bars 105, 106 and 107 are arranged on the other side of the block 57 so that the whole device, when assembled, has a rectangular cross-section making a very compact structure. A cover 12' 5 (Fig. 3) for the housing 12 is provided with an expanded transverse portion 57' which comes into close engagement with the upper face of the block 57 and the upper surfaces of the sliding bars 102 and 107 thereby holding the whole mechanism intact within the housing. Fig. 5 illustrates the arrangement of the several shifting bars relative to the actuating mechanism comprising the block 57 when the device is assembled.

20 Fig. 11 is a perspective view of the shifting bar 106 and Fig. 12 is a view of the forked member 47 which is adapted to be secured to the downwardly projecting lug 49 by means of a screw bolt passing through the opening 140 and secured in the bolt hole 141.

In order to understand the operation of my present gear shifting device, it may be considered in connection with the apparatus of Figs. 1 and 3 wherein it is shown in connection with the variable speed transmission mechanism of the automobile. When the indicating mechanism mounted upon the steering wheel post 2 is positioned at "neutral" and the clutch pedal 14 occupies its normal 35 position, then the elements of the gear shifting device occupy the positions shown in Fig. 4. In this view, all the sliding or shifting bars of Fig. 10 occupy "neutral" to accord with the setting of the index finger 4 of the pre-selecting mechanism. As a consequence, the front group of upstanding teeth 111, 109, 113, 114, 123 and 126 severally secured to the sliding bars, are arranged in a front co-incident plane and, similarly, the 40 rear group of upstanding teeth 115, 116, 100 and 127 (Fig. 10) are likewise arranged in a rear co-incident plane since, in this exemplification, the length of throw of the speed change gears 43 and 44 for all speed changes 45 is the same. It is to be noted that the front group of upstanding teeth form a circular segment which is broken at its upper portion thereby permitting the latch member 81 to be moved transversely of the plane of front teeth 50 forming this circular segment. The latch portion 82 of the latch member 81 is extended upwardly to its foremost position, since the actuator comprising the cylindrical member 79 and the tubular member 59 are rotatably 55 positioned to permit this.

The rotatable positions of the cylindrical member 79 and the tubular member 59 are controlled through the pre-selecting mechanism 4 and, therefore, when the pre-selecting mechanism indicates "neutral", the latch 81

occupies the angular position shown in Fig. 4. Again, the longitudinal positions of the cylindrical member 79 and the tubular member 59 are controlled by the clutch pedal 14 which, on being restored to normal position by 70 reason of the compression spring 21 of the clutch mechanism, causes these two members of the actuator mechanism to be likewise restored to their normal longitudinal positions. The cylindrical member 79 and the 75 tubular member 59 are shown as occupying their normal longitudinal positions in Fig. 7 but, however, they are not shown as occupying "neutral" since they have been rotated from "neutral" through the agency of the 80 pre-selecting mechanism, as will be herein-after described. For the moment, however, it may be considered that the members 59 and 79 with their appurtenances occupy normal position when they are moved rearwardly 85 in the gear shifting mechanism as far as possible, this rearward movement being effected through the return of the clutch pedal 14 to its normal position, which occurs 90 when the foot of the operator is removed from the clutch pedal 14. When the actuator mechanism (Fig. 9) comprising the members 59 and 79 and the latch members 81, 85 and 86 occupies its normal position, it may be rotated to "neutral" as shown in Fig. 4 by means of 95 the pre-selecting mechanism. When the actuator mechanism occupies "neutral", the clutch pedal 14 may be actuated throughout its full range of travel without moving the sliding bars 102, 103, 104, 105, 106 and 107 from their neutral positions of Fig. 4. When the clutch pedal is depressed to its lowermost position during the time that the device is in "neutral", the cylindrical member 79 is advanced in unison with the clutch pedal to its 100 foremost position wherein the latch member 81 extends upwardly and forwardly of the front group of upstanding teeth that are severally secured to the sliding bars. The selective neutralizer 60, during the time that 105 the clutch pedal 14 is depressed to its lowermost position, closely abuts against the rear faces of the upstanding teeth of the front group. As a result of the selective neutralizer 60 being thus limited in its forward travel, the tubular member 59 is also retained at the rear of the front group of upstanding teeth since the selective neutralizer 60 and the tubular member 59 form a unitary structure. It is to be observed that when the selective 110 neutralizer 60 closely abuts the rear faces of the upstanding teeth comprised in the front group, engagement between the cylindrical member 79 and the tubular member 59 is released through the conjoint action of the latch members 85 and 86, as hereinbefore explained. As the selective neutralizer 60 closely approaches the rear faces of the upstanding teeth of the front group and the members 59 115 and 79 are released, the sliding bars are pre- 120

vented from being moved longitudinally by reason of the various poppets and the interlock and the geared connection between each pair of bars.

Assuming that my gear shifting device occupies "neutral" and that the clutch pedal 14 is in its normal position, pre-selection to a subsequent speed change or braking action may be effected by positioning the index finger 4 to that notch on the indicating sector 5 which corresponds to the desired operation to be effected. The actuator mechanism, comprising the members 59 and 79, may thereby be rotated into any one of its various positions since the latch member 81 is offered no lateral obstruction since, in this instance, the latch member 81 is disposed intermediate the rear faces of the front group of upstanding teeth and the front faces of the rear group of upstanding teeth. When the actuator mechanism is in any position other than "neutral", the latch member 81 will be obstructed in its forward longitudinal movement by at least one of the upstanding teeth comprised in the front group.

When the pre-selecting mechanism has been set to indicate a speed change to "first", and a subsequent actuation of the clutch pedal 14 has performed this shifting operation, the sliding bar 105 (Fig. 7) will be advanced to its foremost position by reason of the engagement effected between the front upstanding tooth 114 and the latch portion 82 of the latch member 81. As the sliding bar 105 has been advanced to its foremost position, the sliding bar 104 which is geared to the sliding bar 105, is advanced to its rearmost position. Consequently, the forward upstanding tooth 113 secured to the sliding bar 104 causes the selective neutralizer 60 and the tubular member 59 to be moved rearwardly to their normal positions, as shown in Fig. 7. In this view, the bars 103 and 106 are shown as occupying "neutral". The bar 105 has been advanced forwardly to "first" and simultaneously therewith the bar 104 has been moved rearwardly a corresponding distance from "neutral". When the cylindrical member 79 is then returned to position upon release of the clutch pedal 14 and after the gear shifting into "first" has been made, subsequent forward movements of the cylindrical member 79 is limited by reason of the latch member 81 being obstructed by the upstanding tooth 116 which is paired with the front upstanding tooth 114 and comprised in the rear group of upstanding teeth. In this instance the upstanding rear tooth 116, which is also secured to the sliding bar 105 is advanced forwardly. Subsequent actuations of the clutch pedal 14 may be limited by the obstruction offered to the latch member 81 by the upstanding tooth 116, except for the further movement allowed by the open slot in the loose connection 24 of Fig. 16. This condition obtains as long as

the pre-selecting mechanism remains in "first". The limited range of travel allowed to the latch member 81 and the cylindrical member 79 suffices to permit engagement and disengagement between the two members 17 and 18 comprising the clutch mechanism. Therefore, it will be observed that after a speed change has been effected and the clutch pedal 14 returned to its normal position, subsequent actuations of the clutch pedal are only permissible, as long as the pre-selecting mechanism is retained in this pre-selected position, to engage and disengage the clutch mechanism. At the same time, these subsequent actuations of the clutch pedal 14 preclude the unmeshing from its driving relation of that slidable gear comprised in the variable speed transmission mechanism which gear has been brought into the pre-selected meshing engagement to effect the desired speed change.

Referring again to Fig. 7, the elements are shown as occupying a position wherein a speed change to first has been effected and the pre-selecting mechanism has then been set to effect a subsequent speed change into "second". As a result, the members 59 and 79 have been rotatably positioned so that the latch member 81 is withdrawn from the obstructing tooth 116 and is placed in alignment with and to the rear of, the upstanding tooth 123 secured to the sliding bar 106. As hereinbefore explained, when the sliding bar 106 is advanced forwardly, a speed change into "second" will be effected. Now, when the clutch pedal 14 is actuated, the first portion of its travel effects disengagement between the clutch members 17 and 18. This, of course, disconnects the driving engine of the automobile from the variable speed transmission mechanism. Further movement of the clutch pedal causes the upstanding tooth 113 and the selective neutralizer 60 which is in contact therewith to move forward simultaneously in order to place the rear face of the upstanding tooth 113 co-incident with the rear faces of the other upstanding teeth comprised in the front group. At the same time, the front upstanding tooth 114 secured to the sliding bar 105 is moved rearwardly into its neutral position and in alignment with the other teeth of the front group. This movement of the sliding bars 104 and 105 causes all of the sliding bars to be restored to their neutral positions and, consequently, all of the speed change gears of the variable speed transmission mechanism are likewise restored to neutral position. Further movement of the clutch pedal 14 brings the latch member 81 into direct engagement with the upstanding tooth 123 secured to the sliding bar 106 and, as a result, the sliding bar 106 is advanced forwardly to effect a speed change into "second", as shown in Fig. 8. Fig. 8 shows the elements occupying the positions that they assume when a speed change into "second" has

been made and while the clutch pedal 14 is held at its lowermost position by the operator's foot. In this instance, all of the sliding bars, excepting the sliding bar 106 and its associated sliding bar 107 upon which the front tooth 126 (Fig. 6) is secured, occupy their neutral positions. The selective neutralizer 60 has been moved rearwardly again by reason of engagement between its front face and the rear face of the upstanding tooth 126. The members 59 and 79 have been released from each other by the coacting latch members 85 and 86 whereby the cylindrical member 79 is permitted to slidely engage with the tubular member 59.

Other speed changes may be effected in the manner described above. It will be observed, however, that it is not necessary to make the speed changes in any particular sequence since the members 59 and 79 with their appurtenances may be rotatably positioned to effect subsequent engagement with any one of the front upstanding teeth severally secured to sliding bars irrespective of the longitudinal position of the cylindrical member 79. Referring to Fig. 7, it will be observed that the members 59 and 79 may be rotatably positioned when the latch member 81 is to the rear of the upstanding teeth of the forward group and, similarly in Fig. 8, the members 59 and 79 may be rotated when the latch member 81 is to the rear of the upstanding tooth 123 but in front of the remaining upstanding teeth comprised in the forward group. Again, the members 59 and 79 may be rotated through the agency of the pre-selecting mechanism irrespective of the position of the clutch pedal 14, after the clutch pedal 14 has been returned to normal position subsequently to effecting a pre-selected gear shift. This will be apparent by referring again to Fig. 7 wherein it will be observed that the members 59 and 79 with the latch member 81 may be rotatably positioned without obstruction as long as the latch member 81 is received in the recess 74 formed in the selective neutralizer 60. The range of longitudinal travel of the latch member 81, when a certain gear shift has been made and the member 79 returned to the position shown in Fig. 7, is limited by the length of this recess 74 formed in the selective neutralizer 60.

In Fig. 16, the elements comprising the gear shifting device are shown in the positions that they occupy after a speed change into "second" has been effected, as shown in Fig. 8, and the clutch pedal 14 has been returned to normal position whereby the latch member 81 is moved rearwardly of the upstanding tooth 100, which is now so positioned that longitudinal forward movements of the latch member 81 are limited thereby. The position of the clutch pedal 14 shown in full lines, is that occupied by the clutch pedal 14 when it is depressed as far as is permitted

by reason of the engagement between the upstanding tooth 100 and the latch member 81. It will be observed that the clutch members 17 and 18 are disengaged from each other and that this disengagement of the clutch to release the automobile engine from driving connection with the variable speed transmission mechanism is established without causing any longitudinal movements of the sliding bar 106. Consequently, the slidable gear actuated by the sliding bar 106 is not disengaged from its meshing relation through which "second" speed is established in the transmission mechanism. This is a very desirable condition since the clutch mechanism may be engaged and disengaged at will through the operation of the clutch pedal 14 without affecting in any manner the meshing connections within the variable speed transmission mechanism. The dotted lines of Fig. 16 illustrate the positions occupied by the various elements when the clutch pedal 14 occupies its normal position.

While I have shown an apparatus which is operated by the positive actuation of the clutch pedal, it is to be noted that the same operations may be performed without using the positive actuation of a clutch pedal. Moreover, I have shown the clutch pedal 14 as the most convenient means only for effecting the desired operations, it being obvious, of course, that any foot pedal may serve the same purposes as the clutch pedal 14.

To understand the braking action which may be effected through the agency of my device, reference may now be had to Figs. 1 and 15. By setting the index finger 4 of the pre-selecting mechanism in that notch formed on the recessed sector 5 which corresponds to the brake, the latch member 81 will be positioned in alignment with, and to the rear of the upstanding tooth 111 secured to the brake shifting bar 102 (Fig. 10). Actuation of the clutch pedal 14 will then move the sliding bar 102 forwardly and the sliding bar 103 to rearwardly. The bar 103 being moved to the rear thus causes the brake rod 31 to be moved likewise thereby drawing the band brakes 38 tightly about the rear wheels of the automobile in the usual manner. As long as the operator's foot is retained upon the clutch pedal 14 to hold it into its lowermost position, a braking action will be strenuously applied to the automobile. In order to hold the band brakes in operative engagement and to permit release of the clutch pedal 14, the mechanism of Fig. 15 is provided which is adapted to be actuated manually and set while the operator's foot holds the clutch pedal 14 downwardly. A toothed sector 150 is mounted upon the steering wheel post 2 in such a position that it is readily accessible to the operator. A lever 151 pivotally mounted upon the sector 150 at 152 is provided with a latching handle 153

which serves to effect engagement and disengagement between a latch member (not shown) mounted in the lever 151 and a toothed segment 154 forming the curved portion of the sector 150. By means of the latching handle 153, which is adapted to be grasped manually by the operator, the lever 151 may be positioned at any desired point upon the sector 150 and retained fixed in this position. A tie rod 155 is pivotally secured at 156 to the lever 151 in such a manner that when the lever 151 is raised upwardly, the tie rod 155 is likewise moved upwardly thus rotating a bell crank lever 157 that is pivoted at 158 to a frame member 159 of the automobile chassis. The lever 157 is mounted below the floor boards of the automobile and is adapted to actuate the tie rod 40 which, through a second rock shaft lever 160 keyed to the rock shaft 35, serves to exert a vigorous pull upon the brake rods 37. Therefore, when the braking means have been actuated and are held in engagement by the clutch pedal 14, the lever 151 may be manually moved upwardly and this, in turn, serves to hold the braking means in continuous engagement. Consequently, the clutch pedal 14 may be released and returned to normal position. This will permit the sliding bars 102 and 103 to return to their neutral positions whereby the device may be again used for effecting any of the operations of which it is capable, for instance, to make any of the speed changes in the transmission mechanism for which it is adapted.

From the foregoing description it will be noted that the selector mechanism for rotating the cylindrical member 79 and the tubular member 59 may be actuated for pre-selectively positioning said members to effect a subsequent and pre-determined speed change, as well as neutral and reverse and the braking action, irrespective of the position of the foot pedal 14 in its path of travel. In other words, a pre-selection to another and subsequent speed changes may be made while one speed change connection in the transmission mechanism is in operation when the clutch mechanism of the automobile is engaged or disengaged and irrespective of the position of the foot pedal 14. It is not necessary, in my present invention, to proceed into the various speed changes or reverse or neutral in any sequence since my selector mechanism is pre-selective from any one speed change to any other speed change. When the emergency braking elements comprising the braking rod 31 and its appurtehances are utilized in my gear shifting device, the braking action may be likewise pre-selected in the same manner as the various speed changes. In order to properly designate this method of selecting speed changes irrespective of the position of the foot pedal 14 and the engagement or disengagement of the clutch

mechanism, I designate my present selecting mechanism as a universal selector, meaning that the speed changes, as well as the braking action, need not be effected in sequence and that pre-selection to a subsequent speed change, as well as to reverse and neutral, may be made irrespective of the position of the foot pedal 14 and whether the clutch mechanism is engaged or disengaged.

It is also to be observed that after a certain speed change has been effected, subsequent actuations of the foot pedal 14 will not operate to disengage any of the gears in mesh in the transmission mechanism for effecting such a speed change unless the universal selector mechanism has been in the interim moved to another position indicating a new speed change. This is permitted, of course, by reason of the selective neutralization effected through the agency of the neutralizer 60 and the forward latch member 81. If the neutralizing mechanism in my present device were not a selective neutralizer, each time that the foot pedal 14 is actuated beyond its clutch-disengaging position, and while the selector mechanism is maintained set for a certain speed change position, the speed-change gears comprised in the transmission mechanism would be thrown into and out of meshing engagement as the foot pedal 14 is depressed downwardly and released. By means of my selective neutralizer I retain the speed change gear in a pre-determined operative position on subsequent actuations of the foot pedal 14 as long as the universal selector mechanism is set for such a speed change.

It will be readily apparent to those skilled in the art that in combination with the braking rod 31 being attached to the sliding bar 103, a forked member to effect a fourth speed change may be connected to the sliding bar 102 which may then be actuated in the proper direction to effect an extra gear shift in the transmission mechanism. In this event, my gear shifting device will be adapted for four-speed operations and the braking action as well as three-speed operations and the braking action. In applying my present gear shifting device to the transmission mechanism of an automobile, it is to be observed that my device forms a part of the transmission mechanism in that the two mechanisms are so inter-related as to form a unitary structure. By reason of this arrangement, the casing enclosing the transmission mechanism is superimposed by my gear shifting device which constitutes a cover for the transmission casing.

While I have thus described a preferred construction, combination and arrangement of the various elements comprising my invention, it is evident to those skilled in the art to which my invention appertains, that various changes may be made without de-

parting from the spirit and scope of my invention. I desire, therefore, that only such limitations be placed upon my invention as are set forth in the appended claims.

5. What I claim as new and desire to secure by Letters Patent of the U. S. is:

1. A gear shifting mechanism comprising a plurality of gear shifting members, an actuator therefor, means for rotating said actuator to selectively position it with reference to said gear shifting members, and means for moving said actuator longitudinally to effect engagement with the preselected gear shifting member to move it into operative position, and means for limiting subsequent movements of said moving means whereby said gear-shifting member remains in its operative position irrespective of subsequent longitudinal movements of said actuator while occupying the same rotatable position.

2. The combination of a variable speed transmission mechanism embodying speed changing elements, means comprising an angularly movable member for severally pre-selecting and shifting said speed changing elements, a clutch adapted to drive the transmission mechanism, a foot pedal operative to engage and disengage said clutch and to shift the pre-selected speed changing element into an operative position to produce a speed change in said transmission mechanism, and means comprising said angularly movable member for positively retaining the shifted speed changing element in its operative position while said foot pedal is operated through its entire path of travel, whereby engagement and disengagement of said clutch with said transmission mechanism is effected.

3. The combination with a variable speed transmission mechanism embodying speed changing elements, of an actuator therefor to effect desired speed changes, said actuator comprising a latch member, means for selectively positioning said actuator angularly with reference to said speed changing elements, a clutch adapted to drive the transmission mechanism, a foot pedal operative to disengage said clutch during a portion of its travel and to actuate said actuator during another portion of its travel to shift the selected speed changing element into operative position, and means for cooperating with said latch member whereby the shifted speed changing element is positively retained in its operative position when said foot pedal is subsequently operated until the angular position of said actuator has been changed.

4. In mechanism of the class described, the combination with variable speed transmission gearing, of a clutch to connect the gearing to a source of power, means to shift some of the gears to produce a desired speed change, selective mechanism for said means, and a foot pedal which operates to control

the operation of said clutch during the first part of the forward movement of the pedal and to positively operate the said means in accordance with the setting of said selective mechanism during the second part of the forward movement of the pedal, and means for limiting the range of movement of the foot pedal until said selective mechanism has been set for another speed change.

5. In mechanism of the class described, the combination with variable speed transmission gearing, of a clutch to connect the gearing to a source of power, means to shift some of the gears to produce a desired speed change, selective mechanism for said means, and a foot pedal which operates to control the operation of said clutch during the first part of the forward movement of the pedal and to positively operate the said means in accordance with the setting of said selective mechanism during the second part of the forward movement of the pedal, and means for limiting subsequent operations of said foot pedal within its clutch-operating range of movement until the selective mechanism has been set for another speed change and said selective mechanism being operative to pre-select any shiftable gear for subsequent actuation irrespective of the position of said foot pedal within its clutch-operating range.

6. The combination with variable speed transmission mechanism embodying speed changing elements, and a clutch to connect the mechanism to a source of power, of means comprising members to actuate said speed changing elements, an actuator for said members, a selector for rotating said actuator to selectively position it with respect to said members, a foot pedal operative to control the operation of said clutch and for moving said actuator longitudinally to engage the selected member and to move it into operative position, each of said members having a projection, and a latch member carried by said actuator for engaging the projection on the shifted member to limit the movement of said actuator, whereby said selected member remains in its operative position irrespective of subsequent operation of said foot pedal and until said actuator is subsequently rotated and longitudinally moved to effect another speed change.

7. The combination with a variable speed transmission mechanism embodying speed changing elements, and a clutch to connect the mechanism to a source of power, of members to severally actuate said speed changing elements, an actuator for said members, a selector for rotating said actuator to selectively position it with reference to said members, and a foot pedal operative to control the operation of said clutch and on its positive actuation for moving said actuator longitudinally to engage the selected member for moving it into operative position, each of said

- members having a projection, and a latch member in longitudinal alignment with, and for engaging the projection on the shifted member to limit the range of movement of the actuator whereby said selected member remains in its operative position irrespective of subsequent movements of the clutch pedal and until the actuator is subsequently rotated by said selector and longitudinally moved by 10 said foot pedal.
8. A device of the character described comprising a central stationary member, a common selector and actuator rotatably positioned in and slidably engaging therewith, a plurality of shifting bars arranged peripherally of said central member and slidably engaging therewith, a selective neutralizer mounted on said common selector and actuator for positioning said shifting bars in neutral, means for rotating said common selector and actuator in order to selectively position it relative to said shifting bars, and means for longitudinally moving said common selector and actuator whereby it operatively engages 20 with a selected shifting bar.
9. A device of the character described comprising a central stationary member, a common selector and actuator rotatably positioned in and slidably engaging therewith, a plurality of shifting bars arranged peripherally of said central member and slidably engaging therewith, a selective neutralizer mounted on said common selector and actuator for positioning said shifting bars in neutral, means for rotating said common selector and actuator in order to selectively position it relative to said shifting bars, and means for longitudinally moving said common selector and actuator to first restore through 30 the agency of said neutralizer said shifting bars to neutral and then to move a selected shifting bar into the desired position to effect that operation which corresponds to the setting of said means that rotates said common selector and actuator.
10. A device of the character described comprising a central stationary member, a common selector and actuator rotatably positioned in and slidably engaging therewith, a plurality of shifting bars arranged peripherally of said central member and slidably engaging therewith, a selective neutralizer mounted on said common selector and actuator for positioning said shifting bars in neutral, manually operated pre-selecting means 40 for rotating said common selector and actuator relative to said shifting bars, and a foot pedal for moving said common selector and actuator longitudinally into operative engagement with a selected shifting bar.
11. A device of the character described comprising a central stationary member, a common selector and actuator rotatably positioned in and slidably engaging therewith, a plurality of shifting bars arranged peripherally of said central member and slidably engaging therewith, a selective neutralizer mounted on said common selector and actuator for positioning said shifting bars in neutral, manually operated pre-selecting means 50 for rotating said common selector and actuator relative to said shifting bars, and a foot pedal which on its positive actuation moves said common selector and actuator longitudinally to first restore said shifting bars to neutral and then to move a selected shifting bar into that operative position which accords with the setting of said pre-selecting means. 75
12. A mechanism of the class described comprising a central stationary member, a plurality of sliding bars which are grouped in pairs that are disposed adjacent to said central member, the bars of each pair being operatively connected to each other to effect oppositely directed movements thereof, a rotatable and slidable common selector and actuator, projections severally mounted on said bars to engage with said selector and actuator when in its various positions, means for rotating said selector and actuator to selectively 80 position it relatively to one of said projections on a selected sliding bar, means to slide said selector and actuator forwardly to move the selected sliding bar forwardly and the other sliding bar constituting the pair rearwardly, and means to return said selector and actuator to normal position whereby subsequent movements of said selector and actuator are limited by reason of engagement effected therebetween and another one of said 85 projections on said selected sliding bar.
13. A mechanism of the class described comprising a central stationary member, a plurality of sliding bars which are grouped in pairs that are disposed adjacent the sides 90 of said central member, the sliding bars of each pair being operatively connected to each other to effect oppositely directed movements thereof, a rotatable and slidable selector and actuator, a pair of longitudinally spaced projections severally mounted on some of said sliding bars which may engage with said actuator and selector when in its various longitudinal positions, means to rotate said selector and actuator to selectively position it relatively to the forwardly positioned projections constituting said pairs of projections, means to slide said selector and actuator forwardly to move said selected sliding bar forwardly and the other sliding bar of the pair rearwardly, and means to return said selector and actuator to normal position whereby subsequent longitudinal movements of said selector and actuator are limited by reason of the obstruction offered by the corresponding 100 rear projection associated with the forward projection on said selected sliding bar. 105
14. A mechanism of the class described comprising a central stationary member, a plurality of sliding bars which are grouped 110

in pairs and disposed adjacent to said central member, the bars of each pair being operatively connected to each other, a rotatable and slideable selector and actuator, a pair of longitudinally spaced projections disposed on some of said bars to engage with said actuator and selector when in its various longitudinal positions, a pre-selecting mechanism for rotatably positioning said selector and actuator relatively to the forward projections constituting said pairs of projections, a foot pedal to slide said selector and actuator forwardly to move a selected sliding bar in one direction and the other sliding bar constituting the pair in the opposite direction, and a spring member to return said actuator and selector to normal position whereby subsequent longitudinal movements of said actuator and selector are limited in range by reason of the obstruction offered thereto by the corresponding rear projection associated with the forward projection of the selected sliding bar.

15. A mechanism of the class described comprising a central stationary member, a plurality of sliding bars which are grouped in pairs that are disposed adjacent to the sides of said central member, the sliding bars of each pair being operatively connected to each other, a rotatable and slideable selector and actuator, a pair of longitudinally spaced projections severally disposed on some of said bars which may engage with said selector and actuator when in its various longitudinal positions, pre-selecting mechanism for rotating said selector and actuator to selectively position it relatively to any one of said forward projections, a clutch pedal to slide said selector and actuator forwardly to move the selected sliding bar into operative position, and a clutch spring member to return said selector and actuator to normal position whereby subsequent longitudinal movements of said clutch pedal are limited in range by reason of engagement established between said selector and actuator and the rear projection associated in the pair with the selected forward projection.

16. A mechanism of the class described comprising a central stationary member, a plurality of sliding bars which are grouped in pairs that are disposed each adjacent to one side of said central member, the bars of each pair being operatively connected to each other, a rotatable and slideable selector and actuator, a pair of longitudinally spaced projections severally disposed on some of said bars which may engage with said selector and actuator when in its various longitudinal positions, pre-selecting mechanism

for rotating said selector and actuator to selectively position it relatively to a forward projection secured to one of said sliding bars, a clutch pedal which on its positive actuation slides said selector and actuator forwardly to move said selected bar into operative position, and a clutch spring member to return said selector and actuator to normal position whereby subsequent movements of said clutch pedal are limited in range by reason of engagement between said selector and actuator and the other rear projection associated in the pair constituting the selected forward projection, said pre-selecting mechanism permitting rotation of said selector and actuator irrespective of the position of said clutch pedal in its path of travel.

17. The combination with a variable speed transmission mechanism embodying speed changing elements, means for severally pre-selecting and shifting said speed changing elements, a clutch adapted to drive the transmission mechanism, a foot pedal which, on movement in one direction, disengages said clutch and shifts the pre-selected speed changing element into an operative position and, on movement in the reverse direction, engages said clutch, a latch member, and a coacting member connected to the shifted speed changing element for cooperating with said latching member for retaining the shifted speed changing element in its operative position on subsequent movements in both directions of said foot pedal until another speed change has been pre-selected.

18. The combination of a variable speed transmission mechanism embodying speed changing elements, an actuator for shifting said speed changing elements, a selector for selectively positioning said actuator with reference to said speed changing elements, a clutch adapted to drive the transmission mechanism, a foot pedal operative to disengage said clutch, means for operating said actuator to shift the selected speed changing element into operative position to effect a speed change when the clutch is disengaged, and coacting means associated with said speed changing elements for cooperation with said actuator whereby movements of said actuator are limited while said foot pedal is subsequently operated for engaging and disengaging said clutch with the transmission mechanism, until said selector has been actuated from the position corresponding to said shifted element.

In witness whereof, I have hereunto subscribed my name.

FERDINAND M. BARTELME.
